(57) **CLAIM**

The ornamental design for an edge-wound resistor, as shown and described.

DESCRIPTION

FIG. 1 is a top second end first side perspective view of an edge-wound resistor showing my new design;

FIG. 2 is a first end view of the edge-wound resistor shown in FIG. 1;

FIG. 3 is a second end view of the edge-wound resistor shown in FIG. 1;

FIG. 4 is a first side view of the edge-wound resistor shown in FIG. 1;

FIG. 5 is a second side view of the edge-wound resistor shown in FIG. 1;

FIG. 6 is a top view of the edge-wound resistor shown in FIG. 1; and,

FIG. 7 is a bottom view of the edge-wound resistor shown in FIG. 1.

All broken lines appearing in the drawings are for illustrative purposes and/or represent unclaimed subject matter and form no part of the claimed design.
